UNITED STATES PATENT OFFICE

2,224,529

LIFT

Irving C. Thompson, Cadillac, Mich., and Frederick W. Sturm, Fort Wayne, Ind.; said Sturm assignor to The Wayne Pump Company, Fort Wayne, Ind., a corporation of Maryland

Application May 31, 1940, Serial No. 337,972

10 Claims. (Cl. 254—144)

This invention pertains to vehicle lifts for hoists.

It is an object of this invention to provide a lift which can be installed without the necessity of digging a foundation therefor.

Another object of the invention is to provide a lift which is inexpensive to make and maintain, and fulfills all requirements of manufacture and service.

10 Still another object of the invention is to provide a lift wherein only a unidirectional motor need be used, and one having safety devices to maintain the lift in any position and to prevent too rapid lowering of said lift.

15 Yet another object of the invention is to provide a lift comparable to a so-called four post lift but which takes up a minimum of floor room and height.

With these and various other objects in view, 20 the invention may consist of certain novel features of construction and operation, as will be more fully described and particularly pointed out in the specification, drawings and claims appended hereto.

25 In the drawings, which illustrate an embodiment of the device, and wherein like reference characters are used to designate like parts—

Figure 1 is a top plan view of a lift or hoist embodying the invention;

30 Figure 2 is a side elevation of the lift shown in Figure 1;

Figure 3 is an enlarged transverse sectional elevation taken substantially in the plane as indicated by the line 3—3 of Figure 1;

35 Figure 4 is an enlarged fragmentary sectional elevation taken substantially in the plane as indicated by the line 4—4 of Figure 1;

Figure 5 is an enlarged end elevation, partly in section, of the operating mechanism for the 40 lift, the same looking toward the right as viewed in Figure 2;

Figure 6 is a transverse sectional elevation taken substantially in the plane as indicated by the line 6—6 of Figure 5;

45 Figure 7 is an enlarged fragmentary sectional elevation taken substantially in the plane as indicated by the line 7—7 of Figure 6;

Figure 8 is a fragmentary sectional top plan view taken substantially in the plane as indicated by the line 8—8 of Figure 7;

Figure 9 is an enlarged end elevation of one of the operating pulleys for the lift, the same showing the centrifugal brake;

55 Figure 10 is an enlarged fragmentary sectional

elevation taken substantially in the plane as indicated by the line 10—10 of Figure 9.

The lift or hoist illustrated is of the so-called free-wheel type, though of course it is to be understood that a roll-on-type of hoist may be used, and, although no chocks are shown as applied to this free-wheel type of lift, it is of course understood that suitable chocks are used in this type of lift.

The lift consists essentially of the front track members, rear track members, a carriage and operating means therefor, and, in the embodiment shown, the front track members comprise a pair of spaced frames 20. Each of said frames is formed of the base members 22 connected to a vertical member 24, said vertical member being suitably connected to a track member 26 which, in the embodiment shown, may be conveniently formed of a channel. Each track member 26 is formed with a sloping portion 28 and the upper slightly sloping portion 30, and vertical and horizontal braces 32 and 34 may be provided between the base, vertical and track members. The portions 30 may conveniently be from 5° to 7° from the horizontal.

25 The carriage 36 includes the forward transverse inverted angular member 38 over which the wheels of the vehicle to be lifted are adapted to be rolled, and axle members 40 and 42 are provided for accommodating the rollers 44 adapted to be received in the spaced tracks 26, the tracks 30 preferably being provided with guards 48, the upper flanges 50 of which overlap the rollers 44.

The spaced longitudinally extending beams 52 are secured to the transverse member 38 by means of the brackets 54. The rear ends of the beams 52 are provided with the journals 56 and 58 through which the axle 60 extends. The ends of the axle are provided with the rollers 62 adapted to be received in the channel shaped 40 tracks 64 of the rear track frames, said rear track frames being preferably spaced apart a distance less than the tread of ordinary vehicles, such as automobiles.

The track members 64 are similar to the track 45 members 26, each having the sloping portion 66 parallel to the sloping portion 28, and the upper slightly sloping portion 68 disposed at the same height as the horizontal portion 30 and having the same angularity. The frame members 64 50 are suitably secured to the vertical spaced uprights 70 and 72, and each frame member 64 and its respective upright are connected together adjacent the bases thereof by means of the angle 74. The axle 60 is provided with the spaced 55

pulleys 76 maintained in fixed position between the inner journals 58 by the spacing tube 78.

The uprights 70 and 72 form means for supporting the operating mechanism, and said uprights are suitably secured adjacent the tops thereof by means of the transverse brace member 80, and are secured adjacent the bases thereof by the brace member 81. The brace member 80 is provided with the spaced fastening means 82 which, in the embodiment shown, are eye bolts to which one end of the cables 84 are secured, said cables passing downwardly and around the pulleys 76, and thence back to be secured at their other ends to the tracked or spiral drums 86 non-rotatably mounted on the shaft 88.

A safety latch 90 is pivotally mounted on the shaft 88, being positioned thereon by means of the spaced collars 89, and said latch is provided with the handhold or handle 92 and the hooked end 94 adapted to latch the carriage 36 by engagement with the tube 78 when the rollers 62 have been moved on to the portions 68 of the tracks 66. The latch may also be provided with the stop 96 adapted to engage the brace member 80 to prevent the latch from falling to a position where it cannot automatically engage the member 78. The latch 90 is preferably provided with the sloping portion 97 adapted to be engaged by the sleeve 78 for moving the latch upwardly when it is being moved to latch engaging position.

The shaft 88 is provided with the gear 98, meshing with the gear 100 non-rotatably mounted on the shaft 102. The shaft 102 is non-rotatably provided with the gear 104 meshing with the gear 106 non-rotatably mounted on the shaft 108. The shafts 88, 102 and 108 are suitably journaled as at 109, 110 and 112 respectively, on the uprights 70 and 72. The shaft 108 is provided with a hand wheel 114 adapted to rotate the shaft 108 for the purpose to be more fully described later.

The shaft 108 is non-rotatably provided with the ratchet 116 adjacent the upright 70. The pawl 118 is pivoted to the shaft 102 and is adapted to be moved to engage the ratchet 116 to prevent clockwise movement of the shaft 108 as viewed in Figure 7. The pawl 118 is provided with the handhold 120 and the locking member 122 pivoted to the pawl as at 124, an extension 126 thereof being provided with the locking ledge 128 adapted to engage one flange of the upright 70 to maintain the pawl in inoperative position. A spring 130 is provided to urge the member 128 toward locking position. It will thus be seen that it is only necessary to move the locking member 122 toward the handhold 120 about the pivot 124 to release the locking ledge 128 from locking position to permit the pawl 118 to be dropped into engagement with the ratchet 116.

The shaft 108 also is provided with the brake drum 132, and the band brake 134 is disposed around said brake drum, said band brake being anchored as at 136 and 138 to the operating lever 140 pivoted as at 142 to the upright 70. This hand brake may be used to check or arrest downward movement of the carriage 36. The shaft 108 may be provided with the socket 144 with a reception of a hand crank 146 for operating the lift in emergencies, and said shaft is non-rotatably provided with the pulley 148 connected by the belt 150 with the pulley 152 provided on the operating shaft of the motor 154, said motor being supported on the upright 70.

The motor 154 is electrically connected through a suitable conduit 158 to the switch 158, and said switch is electrically connected to a suitable

source of supply (not shown) through the conduit 160. The switch 158 is provided with the operating lever 162 for opening and closing said switch, and said lever 162 is provided with the resilient extension 164 extending upwardly in the path of the axle 160 whereby engagement by said axle in moving the carriage 36 on raised position 68 will move the member 164 to open the switch.

The stationary brake drum 166 is secured as at 168 to the upright 70 and is disposed concentrically with the shaft 108. The pulley 148 is bossed as at 170 and the shaft 172 is journaled therein. The shaft 172 is non-rotatably provided with the centrifugal lever 174 having the weighted end 176 extending inwardly toward the shaft 108, the end being bifurcated to embrace said shaft. The lever 174 is urged in a clockwise direction, as viewed in Figure 9, by means of a spring 178, one end of said spring being secured as at 180 to the pulley, the other end of said spring being secured as at 184 to the lever, the head of the lever being provided with a rubber block 186 for cushioning the head against the central hub of the pulley. The inner end of the shaft 172 is non-rotatably provided with the lever 188 loosely pivoted as at 190 to the brake shoe 192 disposed to have braking cooperation with the brake drum 166 upon a predetermined speed of rotation of the pulley 148 in a counterclockwise direction as viewed in Figure 9, that is, when the lift is being lowered. The gear train 88, 100, 104 and 106 may be suitably enclosed by means of the housing 194, and the pulleys 148 and 152 and the centrifugal brake may likewise be enclosed in a housing 196.

In operation of this form of lift, let it be assumed that the carriage is in lowered position and a vehicle, such as an automobile, has been rolled between the frames 20 of the member 36 so that the spaced members 52 of the carriage 36 are disposed in proper position beneath the vehicle. The motor switch 158 may then be closed by means of the lever 162, and operation of the motor causes rotation of the shaft 108 through the pulleys 152 and 148, and the belt 150. Rotation of the shaft 108 causes rotation of the shaft 88 through the gear train 106, 104, 100 and 98, thus causing rotation of the drums 86. Rotation of the drums 86 will wind the cables 84 around said drums, drawing the carriage toward the left as viewed in Figures 1 and 2, to cause the carriage to move up the inclined members 26 and 66.

The carriage will move upwardly until the rollers 44 and 62 are respectively received on the portions 30 and 68, at which time the lever 162 may be manually operated to switch open position, or the axle 60 may open the switch by engagement and movement of the member 164. At that time the hook 90 will engage the axle and tubular member 60-78 to prevent accidental lowering of the carriage.

When it is desired to lower the carriage, and in the event that the motor 154 is not a reversible motor, which of course would permit of a cheaper construction being used, the latch 90 is lifted by the lever 92 and the hand wheel 114 is rotated to slacken the cables 84 by rotation of the shaft 88 by means of the gear train 106, 104, 100 and 98. Too rapid downward movement of the carriage 36 is checked by the centrifugal brake because, if the carriage moves downwardly too quickly, the shaft 88 will cause rotation of the shaft 108 to cause the lever 174 to move in a counterclockwise direction about its pivot 172, thus causing the brake shoe 192 to engage the brake drum 166.

In the event it is desired to stop the carriage

at any point, the brake lever 140 may be operated to completely arrest rotative movement of the shaft 108 through the brake band 134 and the brake drum 132. The shaft may be locked in 5 any position by means of the pawl 118 by moving said pawl into engagement with the ratchet 116 in a manner already described.

It is to be understood that we do not wish to be limited by the exact embodiment of the device 10 shown, which is merely by way of illustration and not limitation as various and other forms of the device will of course be apparent to those skilled in the art without departing from the spirit of the invention or the scope of the claims.

15 What is claimed:

1. In a lift, the combination of spaced pairs of track members, each of said track members having parallel inclined tracks, each inclined at substantially the same angle, each track terminating 20 at its highest point with a portion of less angularity than said first named angle, the track members of one pair of said track members being spaced apart a greater distance than the track members of the other of said pair, a carriage, 25 anti-friction members adjacent each end of said carriage disposed to be moved along said tracks, operating mechanism disposed on one of said pairs of track members for moving said carriage along said tracks to raised or lowered position, 30 said operating mechanism including actuating means, a shaft driven by said actuating means for controlling movement of said carriage, and a centrifugal brake operative to reduce the speed of said shaft when said actuating means is inoperative.

2. In a lift, the combination of spaced pairs of track members, each of said track members having parallel inclined tracks, each inclined at substantially the same angle, each track terminating 40 at its highest point with a portion of less angularity than said first named angle, a carriage, anti-friction members adjacent each end of said carriage disposed to be moved along said tracks, operating mechanism disposed on one of said 45 pairs of track members for moving said carriage along said tracks to raised or lowered position, said operating mechanism including actuating means, a shaft driven by said actuating means for controlling movement of said carriage, a 50 brake member for checking the downward movement of said carriage, means for preventing movement of said shaft and to maintain said carriage in any selected position on said tracks, and means adapted to be actuated by said carriage for rendering said actuating means inoperative when said carriage is moved to a predetermined position.

3. In a lift, the combination of spaced pairs of track members, each of said track members having parallel inclined tracks, each inclined at substantially the same angle, each track terminating 60 at its highest point with a portion of less angularity than said first named angle, the track members of one pair of said track members being spaced apart a greater distance than the track members of the other of said pair, a carriage, anti-friction members adjacent each end of said carriage disposed to be moved along said tracks, operating mechanism disposed on one of said 65 pairs of track members for moving said carriage along said tracks to raised or lowered position, said operating mechanism including actuating means, a shaft driven by said actuating means for controlling movement of said carriage, a 70 brake member for checking the downward movement of said shaft and to maintain said carriage in any selected position on said tracks, means adapted to be actuated by said carriage for rendering said actuating means inoperative when said carriage is moved to a predetermined position, and means for releasably holding said carriage in said predetermined position.

4. In a lift, the combination of spaced pairs of track members, each of said track members having parallel inclined tracks, each inclined at substantially the same angle, each track terminating 75 at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, a brake member for checking the downward movement of said carriage, and means adapted to be actuated by said carriage for rendering said actuating means inoperative when said carriage is moved to a predetermined position.

5. In a lift, the combination of spaced pairs of track members, each of said track members having parallel inclined tracks, each inclined at substantially the same angle, each track terminating at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, a brake member for checking the downward movement of said carriage, and means adapted to be actuated by said carriage for rendering said actuating means inoperative when said carriage is moved to a predetermined position.

6. In a lift, the combination of spaced pairs of track members, each of said track members having parallel inclined tracks, each inclined at substantially the same angle, each track terminating at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, a brake member for checking the downward movement of said carriage, and means adapted to be actuated by said carriage for rendering said actuating means inoperative when said carriage is moved to a predetermined position.

7. In a lift, the combination of spaced pairs of track members, each of said track members having parallel inclined tracks, each inclined at substantially the same angle, each track terminating 75 at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, a brake member for checking the downward movement of said shaft and to maintain said carriage in any selected position on said tracks, means adapted to be actuated by said carriage for rendering said actuating means inoperative when said carriage is moved to a predetermined position, and means for releasably holding said carriage in said predetermined position.

8. In a lift, the combination of spaced pairs of track members, each of said track members having parallel inclined tracks, each inclined at substantially the same angle, each track terminating 75 at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, a 80 brake member for checking the downward movement of said shaft and to maintain said carriage in any selected position on said tracks, means adapted to be actuated by said carriage for rendering said actuating means inoperative when said carriage is moved to a predetermined position, and means for releasably holding said carriage in said predetermined position.

ing at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, a brake member for checking the downward movement of said carriage, means adapted to be actuated by said carriage for rendering said actuating means inoperative when said carriage is moved to a predetermined position, and means for releasably holding said carriage in said predetermined position.

8. In a lift, the combination of spaced pairs of track members, each of said track members having parallel inclined tracks, each inclined at substantially the same angle, each track terminating at its highest point with a portion of less angularity than said first named angle, the track members of one pair of said track members being spaced apart a greater distance than the track members of the other of said pair, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, a brake member for checking the downward movement of said carriage, means adapted to be actuated by said carriage for rendering said actuating means inoperative when said carriage is moved to a predetermined position, and means for releasably holding said carriage in said predetermined position.

9. In a lift, the combination of spaced pairs of track members, each of said track members having parallel inclined tracks, each inclined at substantially the same angle, each track terminating at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, and means adapted to be actuated by said carriage for rendering said actuating means inoperative when said carriage is moved to a predetermined position.

10. In a lift, the combination of spaced pairs of track members, each of said track members having parallel inclined tracks, each inclined at substantially the same angle, each track terminating at its highest point with a portion of less angularity than said first named angle, a carriage, anti-friction members adjacent each end of said carriage disposed to be moved along said tracks, operating mechanism disposed on one of said pairs of track members for moving said carriage along said tracks to raised or lowered position, said operating mechanism including actuating means, a shaft driven by said actuating means for controlling movement of said carriage, means adapted to be actuated by said carriage for rendering said actuating means inoperative when said carriage is moved to a predetermined position, and means for releasably holding said carriage in said predetermined position.

IRVING C. THOMPSON,
FREDERICK W. STURM.
